LOCOMOTIVE

Charles D. Barrett, Altoona, Pa.

Application July 4, 1945, Serial No. 603,118

9 Claims. (Cl. 105—82)

1

This invention relates generally to locomotives, and has reference more particularly to steam locomotives of the twin engine type wherein two sets of driving wheels independent of connection with each other are separately powered.

In a steam locomotive the power developed by the reciprocating engine or the turbine as the case may be, is transmitted through connecting rods or gearing to the driving wheels which develop a draw bar pull equal but opposite to the frictional force between the rail and the said wheels. This latter force cannot be in excess of the weight of the drivers multiplied by the coefficient of the friction between the rail and the wheels. If the engine of the locomotive develops a greater force than the above the drivers will slip. Conversely, if the weight on the drivers decreases, the maximum tractive force that can be exerted without slipping will be correspondingly decreased. It is therefore important that the weight on the drivers be not reduced beyond the value selected by the designer. The maximum weight to be carried by the drivers is limited by the strength of bridges and rails and by other factors. Any additional weight must be carried by the smaller wheels of the associated auxiliary swivel guide truck. Since the total weight of a locomotive in service remains practically constant, it follows that the weight on the drivers will remain constant in the absence of changes in the distribution of the load between them and the smaller truck wheels. Change in the distribution of weight from one pair of drivers to an adjacent pair coupled to the first pair by side rods or gearing, will be of no consequence because one pair cannot slip unless the other pair connected to it by the rods or gearing also slips. Hence the power not transmitted by the pair of drivers carrying the decreased weight will be transmitted by the heavily loaded drivers. In the older types of rigid frame locomotives in which small wheeled swivel trucks were used ahead of the drivers only, there was little chance of transfer of the weight from the drivers to the smaller wheels. However, with the evolution of the more modern rigid frame steam locomotives, as the boilers were lengthened it became necessary to employ both in the single and twin engine types, auxiliary swivel trucks not only forwardly of the drivers, but rearwardly thereof as well, in order that the weight of the boilers might be adequately supported throughout their lengths. This altered construction gave rise to slippage upon easement of the load on the drivers and transfer thereof to the leading and trailing auxil-

2
iary trucks incident to travel over track sections with normal elevational irregularities. In other words, under the condition stated, the boilers would be supported after the manner of a bridge beam by the small wheeled end trucks, with the drivers "floating" and thus failing to effectively react tractionally with the rails. In an attempt to preclude slippage, spring and lever equalizing systems were devised with a view toward uniformly distributing the load between the drivers and the smaller end truck wheels. However, the great number of short levers employed in such equalizing systems, have fulcrum pins which are heavily loaded so that their action is attended by high friction. Moreover slight changes in angularity altered the effective length of the levers, and the connecting links between the levers and the springs would rub against the locomotive frame and cause additional friction. As a result of these and other factors, distribution of the weight was frequently found to be far from that intended by the designer. The equalizing systems could not therefore be relied upon to always maintain a correct weight distribution on the drivers. Such conditions are especially serious in the operation of rigid frame twin engine locomotives because the two separately powered sets of drivers are not connected. Accordingly slipping may occur in one set of drivers of such a locomotive at a time when the weight on that set is reduced, although the total weight on the drivers is normal.

The chief aim of my invention is to overcome the various drawbacks which have been pointed out above in connection with the prior art locomotive construction. This objective is realized in practice as hereinafter more fully disclosed, through provision in a locomotive having a boiler and a pair of separately powered engine units with plural drivers and associated smaller wheeled swivel trucks, of transverse axis pivot supports for the boiler at single locations on the frames of the respective units, so disposed longitudinally of the locomotive that equal loads are imposed upon said units, with distribution of the load between the drivers and the small auxiliary wheels of the respective units in a definite ratio; and through the further provision of guide means whereby said power units are connected to the boiler at other points in such a way as to be held in longitudinal alignment with the boiler as they rock on said transverse axis pivot supports incident to traveling over elevational irregularities in the track rails.

Other objects and attendant advantages will

appear from the following detailed description of the attached drawings, wherein Fig. 1 is a skeletonized view in side elevation of a twin engine locomotive conveniently embodying my invention.

Fig. 2 is a skeletonized view showing the locomotive of Fig. 1 in top plan.

Fig. 3 is an exaggerated diagrammatic view exaggeratedly showing the pivotal action between the trucks and the boiler of my improved locomotive incident to travel over vertical track irregularities.

Fig. 4 is a view similar to Fig. 1 showing an alternative embodiment of my invention.

Fig. 5 is a view showing the locomotive of Fig. 4 in top plan.

Fig. 6 is a fragmentary plan view of a locomotive showing still another alternative embodiment of my invention.

Fig. 7 is a fragmentary view drawn to a larger scale showing, in side elevation, a transverse boiler supporting pivot means employed in connection with the locomotive of Fig. 1.

Fig. 8 is a fragmentary view showing the pivot means of Fig. 7 in front elevation.

Fig. 9 is a fragmentary view on a larger scale showing, in side elevation, another transverse pivot boiler supporting means of the locomotive illustrated in Fig. 1.

Fig. 10 is a fragmentary view, partly in front elevation and partly in section, of the means shown in Fig. 9.

Fig. 11 is a fragmentary view, in front elevation on a larger scale, of a guide means employed in the locomotive of Fig. 1.

Fig. 12 is a horizontal section taken as indicated by the angled arrows XII—XII in Fig. 11.

Figs. 13 and 14 are views corresponding to Figs. 11 and 12 of a guide means associated with the locomotive of Fig. 6, Fig. 14 being a horizontal section taken as indicated by the angled arrows XIV—XIV in Fig. 13.

Fig. 15 is a view in top plan on an enlarged scale of a guide and cushioning means associated with the locomotive of Fig. 6.

Fig. 16 is a sectional view of the means of Fig. 15 taken as indicated by the angled arrows XVI—XVI in the latter figure.

Fig. 17 is a transverse section of the means of Fig. 15 taken as indicated by the angled arrows XVII—XVII in Fig. 16.

Fig. 18 is a fragmentary detail view in plan showing the type of universal coupling which is used to connect the frames of trucks of the locomotive shown in Fig. 6; and

Fig. 19 is a fragmentary view in side elevation of said coupling means.

Referring first more particularly to Figs. 1 and 2 of these drawings, the locomotive there more or less diagrammatically illustrated and embodying my invention in one form has a horizontally-elongate boiler 20 and two independently powered truck units which are comprehensively designated respectively by the numerals 21 and 22. These powered units 21 and 22 are generally similar in construction, each being shown as having its own axle journal frame 23, two pairs of side-rod-connected drivers 24 actuated in this instance by steam cylinders 25, and a conventional spring equalizing system indicated at 26. Associated with the powered truck units 21 and 22 are a small wheeled pilot truck 27 and a similar small wheeled trailer truck 28 which are pivotally connected to the frames 23 of said units at 27x and 28x respectively. It is to be understood that one

75

pair of drivers 24 of each truck 21 and 22 is fitted with lateral motion spring devices, such as are ordinarily used on long rigid frame locomotives, for capacity to shift sidewise and thus facilitate travel of the locomotive on curved track. As shown, the frames 23 of the engine units 21 and 22 are serially connected by a coupling link 29 which permits vertical movement to take place between them.

For the purpose of sustaining the boiler 20 in accordance with my invention, I have provided transverse pivot supports 35 and 36 which are illustrated in detail respectively in Figs. 7, 8, and Figs. 9, 10, and which are duplicated at opposite sides of the locomotive. As shown in Figs. 7 and 8 each support 35 comprises a strut bracket 37 which is secured to the mud ring of the fire box at one side of the boiler 20 and has a foot 38 loosely engaged with capacity to slide longitudinally of the locomotive in a dovetail groove of a shoe element 39 so as to accommodate lengthwise expansion and contraction of the boiler. At the bottom, the element 39 is formed with a concaved transverse groove 40 for pivotal engagement with a rounded projection 41 recessed into a pad 42 on the top of the frame 23 of the powered unit 22 at the corresponding side of the locomotive. Safety hold-down or keeper lugs 43 overreach flanges 44 on the shoe element 39 to prevent dislocation of the latter while permitting its pivotal action about the projection 41. As shown in Figs. 9 and 10, each support 36 has a foot piece 46 which is secured directly to the shell of the boiler 20 adjacent the front end of the latter, and the bottom of which is provided with a concaved transverse groove 47 for pivotal engagement with an upwardly rounded projection 48 recessed into a pad 49 on top of the main frame 23 of the powered unit 21. Here, as in the case of the support 35, safety stop lugs 50 cooperate with side flanges 51 on the element 46 to limit vertical movement between the foot piece 46 and the lug 48.

Disposed forwardly and rearwardly of the transverse pivot supports 35 and 36 are guides 52, 53 and 54, 55 respectively. These guides 52-55 are duplicates of each other and, as instanced in Figs. 11 and 12, each of them includes a bracket 56 with a pendent tongue 57 which is secured to the bottom of the boiler 20, and a pair of fixed guide lugs 58 on the top of the main frame 23 of the powered unit 21 or of the powered unit 22 as the case may be.

Due to the aforescribed construction and arrangement, it will be seen that the powered trucks 21 and 22 are free to rock up and down independently on the transverse pivot supports 35 and 36 during travel of the locomotive over vertical irregularities in the track as exaggeratedly shown in Fig. 3 while being held in alignment with the boiler 20 by the guides 52, 53, and 54, 55. In practice the supports 35 and 36 are so located with respect to the frames of the powered truck units 21 and 22 as to insure, under all conditions of operation, equal sharing of the load between the two powered trucks, as well as even distribution of the weight between the drivers and the wheels of the respectively associated auxiliary pilot and trailer trucks 27 and 28. Under these conditions therefore, the likelihood of slippage of one set of drivers with respect to the other is definitely precluded.

The locomotive of Figs. 4 and 5 is identical with that of Figs. 1 and 2 except that here cushioning devices 60 are used at the back end of the fire

box in addition to the guides 55a. These cushioning devices 60 each include a helical compression spring 61 whereof the ends are seated in pocketed pads 62 and 63 respectively on the boiler 20a and on the main frame 23a of the rear powered truck unit 22a. The cushioning devices 60 serve to resiliently support the overhanging rear end of the boiler 20a and transmit part of the boiler load to the rear end of the frame 23a. The position of the resultant boiler load is thus nearer the rear end of the main frame than it would be if all the boiler load were transferred to the main frame 23a by the supports 35a and 36a. Due to the flexibility of the cushioning devices 60 the position of the resilient boiler load on the main frame 23a remains approximately fixed even when there is a slight angular movement in the boiler plane between the boiler 20a and the main frame 23a. All the other appointments of the locomotive of Figs. 4 and 5 may be like the locomotive of Figs. 1 and 2, these being designated by the same reference numerals previously employed with addition in each instance of the letter "a" for convenience of more ready distinction.

In the locomotive of Fig. 6, the boiler (not shown) is sustained as in the first described embodiment through transverse pivot supports 35b and 36b by the main frame 23b of the powered truck units 21b and 22b. The auxiliary guide devices 52b, 54b are however of slightly different construction from the corresponding devices 52 and 54 of the first embodiment, one of them being separately illustrated in detail in Figs. 13, 14. Here, instead of a tongue, the lug piece 56b is provided with a pendent pivot shank 57b for a block 65 which engages between guide lugs 58b on the truck frame 23 and which allows the truck to swivel slightly without restraining free longitudinal expansion and contraction of the boiler. Here also, instead of the devices 53, 55 of the first embodiment, I substitute combined guide and cushioning devices 66, one of which is shown in detail in Figs. 15, 16 each including a pendent yoke bracket 70 which is secured to the boiler at the bottom and which has transversely apertured terminal bosses 71, 72 on its yoke extremities. Confined to axial movement in the bosses 71 and 72 are hollow bolt elements 73 and 74 which are telescopically engaged with each other and which respectively have stop collars 75. A helical spring 76 in compression between the stop collars 75 normally acts to keep the bolt elements 73 and 74 yieldingly positioned as shown with their outer ends protruding beyond the bosses 71 and 72 in readiness to cooperate with spaced lug projections 77 and 78 affixed to the top of the frame 23b of the powered truck. In Fig. 6, the truck units 21b and 22b are thus capable of independently swinging laterally about the pivots 51b to a small extent as the locomotive rounds sharply a curved track, such motion being cushioned by the action of the devices 66. This action of course does not interfere with the rocking movement of the trucks 21b, 22b on the pivots 48b of the devices 35b and 36b as surface irregularities of the track are encountered by their respective wheels. Since in the locomotive of Fig. 6, the truck frames 23b are accorded slight independent angular movement both vertically and laterally in relation to the boiler, I connect the frame with a universal coupling 29b of the type illustrated in detail in Figs. 18 and 19. As shown, the coupling 29b comprises a plurality of links 80 which at their ends are pivoted to transverse pins 81 in yoke heads 82 which are in turn pivoted on vertical axis pins 79

83 in the contiguous end portions of the frames 23b. The last described arrangement is particularly advantageous in connection with long high speed locomotives with 2-6-6-4 or 4-8-8-4 wheel arrangements where a small amount of controlled lateral freedom is desirable for ability to traverse sharp curves in the trackage.

Having thus described my invention, I claim:

1. In a locomotive, a horizontally-elongate boiler; a pair of serially-arranged supporting trucks each having plural drivers and its own axle journal frame and provisions to permit rounding of curves, transverse axis fulcrum means whereby the boiler is supported on each track and whereby each truck is permitted to rock up and down relative to the boiler, each such fulcrum means including a pair of crosswise-aligned pivotal connections between the truck and the boiler respectively at opposite sides of the locomotive; and guide means spaced from the respective fulcrum means longitudinally of the locomotive for maintaining the two trucks longitudinally aligned with the boiler, each such guide means comprising interengaging components respectively on the trucks and on the boiler.

2. A locomotive according to claim 1, wherein there are two guide means for each truck, one in advance of and the other to the rear of the fulcrum means of the truck.

3. A locomotive according to claim 1, further comprising a coupling link whereof the opposite ends are connected to the contiguous ends of the two trucks respectively by transverse axis pivots.

4. A locomotive according to claim 1, wherein the components of one pivotal support are interconnected for relative pivotal movement only, and wherein the components of the other pivotal support are interconnected for relative pivotal movement as well as sliding movement to permit longitudinal expansion and contraction of the boiler.

5. A locomotive according to claim 1, wherein each guide means comprises a longitudinally slotted member affixed to the truck, and a roller which is freely rotative about a centrally located pendent stud projection on the boiler, and which extends part way into the slot of the aforesaid member to permit up and down rocking movement of the corresponding truck on the corresponding transverse axis fulcrum means.

6. In a locomotive, a horizontally-elongate boiler; a pair of serially-arranged trucks each having plural drive wheels and its own axle frame and provisions to permit rounding of curves; and a transverse axis pivot means for supporting the boiler at one location only on the frame of each truck, each such pivot means including two members at each side of the locomotive respectively secured to the boiler and to the truck frame, one having a transverse groove, and the other having a rounded projection in engagement with said groove.

7. In a locomotive, a horizontally-elongate boiler; a pair of serially-arranged trucks each having plural drive wheels and its own axle frame and provisions to permit rounding of curves; a transverse axis pivot means for supporting the boiler at one location only on the frame of each truck, each such pivot means including two members at each side of the locomotive respectively secured to the boiler and to the truck frame, one having a transverse groove, and the other having a rounded projection in engagement with said groove; and guide means spaced from the respective fulcrum means longitudinally of the locomotive for maintaining the two trucks

longitudinally aligned with the boiler each such guide means comprising a pendant tongue on the boiler and a longitudinal guide groove on the top of the corresponding truck frame engaged by said tongue.

8. In a locomotive, a horizontally-elongate boiler; a pair of separately-powered serially-arranged trucks each having plural driving wheels and its own axle journal frame; transverse axis pivot means for supporting the boiler at one location only on the frame of each truck with the trucks free to rock independently about the respective pivotal supports; and guide means spaced from the respective pivot means for controlling relative longitudinal alignment of the boiler and the two trucks while permitting only limited lateral pivoting of each truck, one guide means for each truck consisting of a vertical pivot permitting swivelling but no lateral movement, and another guide means for each truck comprising a pendant member on the boiler, stops on the corresponding truck frame at opposite sides of the pendant member, and resilient means operative between said pendant member and said stops to permit a small amount of lateral movement.

9. In a locomotive, a horizontally elongate boiler with a fire box at its rear end; a pair of separately-powered serially-arranged trucks each

5 having plural driving wheels and its own axle journal frame; a transverse axis pivot means for supporting the boiler at one location only on the frame of each truck, the rear pivotal support being located beneath the front end of the fire box of the boiler; and a resilient auxiliary sustaining means interposed between the fire box and the top of the rear truck frame.

CHARLES D. BARRETT.
